UNITED STATES PATENT OFFICE

128,316

DESIGN FOR A COMBINED WATER FILTER AND FAUCET

Joseph T. Roffy, Los Angeles, Calif., assignor of one-half to Abraham Rothenberg, Los Angeles, Calif.

Application March 4, 1941, Serial No. 99,342

Term of patent 14 years

To all whom it may concern:

Be it known that I, Joseph T. Roffy, a Hungarian National, residing at Los Angeles, in the county of Los Angeles and State of California, have invented a new, original, and ornamental Design for a Combined Water Filter and Faucet, of which the following is a specification, reference being had to the accompanying drawing, forming a part thereof.

Fig. 1 is a perspective view of the front and one side of a combined water filter and faucet showing my new design; and

Fig. 2 is a fragmentary perspective view thereof, as viewed from the opposite side of Fig. 1, with portions of the faucet broken away for convenience of illustration.

The dominant features of the design reside in the portions shown in full lines.

I claim:

The ornamental design for a combined water filter and faucet, as shown and described.

JOSEPH T. ROFFY.
